UNITED STATES PATENT OFFICE.

CHARLES F. HOOFER, OF SEATTLE, WASHINGTON.

TIME-CONTROLLING DEVICE FOR AUTOMATIC FLANGE OILERS.

Application filed April 7, 1920. Serial No. 371,986.

To all whom it may concern:

Be it known that I, CHARLES F. HOOFER, a citizen of the United States of America, and resident of the city of Seattle, county of 5 King, and State of Washington, have invented certain new and useful Improvements in Time-Controlling Devices for Automatic Flange Oilers, of which the following is a specification.

10 My invention relates to a device intended to control the time during which a motive fluid, as air, will continue its action upon a mechanism after it has been applied by the action of some other mechanism. The 15 device thus acts as a delayed cut-off for the air supply.

The object of my invention is to insure the application of air to a mechanism for a determined period after it has been applied 20 thereto, in case where the applying means may act only momentarily.

The novel features of my invention upon which I desire patent protection will be first described and then particularly defined in the claims.

In the accompanying drawings I have shown my invention in the form of construction which I have adopted for one particular use.

30 Figure 1 is a central vertical section taken lengthwise of the device or on the line 1—1 of Figure 6.

Figure 2 is a section on the line 2—2 of Figure 1.

35 Figure 3 is a bottom face view of the plunger head.

Figure 4 is a horizontal section on the plane of the line 4—4 of Figure 1.

Figure 5 is a view of the end of the device which is at the left hand in Figures 1 and 4.

Figure 6 is a horizontal section taken on the line 6—6 of Figure 1.

Figure 7 is an end view and Figure 8 a 45 perspective of the valve opening cam bar.

My invention is illustrated in the accompanying drawings, and will be hereinafter described, in the form of construction which has been designed for use with flange or rail 50 oiling devices which are operated by air. The purpose of the device is to provide means whereby when the air supply valve has been once opened, it will be kept open not less than a certain minimum time, even 55 though the opening means may sooner cease to act. It may thus be correctly called a

delayed-closing device. It is evident that it may be applied to other purposes than the particular one above mentioned, or wherever like conditions are found and it be 60 desired to insure a minimum opening time of the supply valve.

The device is enclosed within a casing 14 having an outward extension 15 which supports a shaft bearing 16, and an adjustment 65 screw 19. A corresponding shaft bearing 17 is employed for supporting the shafts 20 and 21 respectively, each of which are provided at their meeting ends with inclined cam facets 23 (see Figures 1 and 4). The 70 shaft 20 has a non-circular portion 24 upon which is loosely mounted a lever 25.

An air pressure valve casing 26 is provided with an open ended cylindrical extension 27 projecting into and secured to the 75 casing 14. A reciprocating piston 28 in the cylinder 27 is adapted to engage one end of the fulcrum lever 29 which is pivoted upon the pin 33. A spring 32 which is carried by the pin 33 is employed to hold the various 80 operative parts in their normal position, as shown in Figures 1 and 6.

A reciprocating connecting rod 34 forming a pair of parallel guides 35 and 35^a, and a circular enlargement 36, has one end pivoted to the lever 29 and the other end pivoted to the plunger head 37.

A non-circular portion 22 of the shaft 21 is mounted between the parallel guide members 35 and 35^a. A dashpot 38 open at its 90 top end and secured to a corresponding opening in the casing 14 is provided with a reciprocating plunger 37. A ball check valve 39, adapted to close during a downward movement, and a permanently open by-pass 95 or vent passage 40, provide means whereby a liquid may be passed through the piston 37. A deflector disk 41 extends over the openings 39 and 40.

The piston 28 is provided, at its lower 100 end, with a cup leather packing 30, above which a chamber or port, formed by reducing the diameter of a central portion of the piston 28, is in communication with the atmosphere through the vent 31. The air 105 pressure valve casing 26, is supplied with an inlet through a pipe 42 and discharges through the pipe 43. A valve 44 having radial guide members 45 is normally held upon its seat by the spring 46 and the screw 110 cap 47. A stem 48 having one of its ends bearing against the opposite side of the

valve 44, extends out of the casing 26, through a packing gland 49 and terminates in engagement with the end of the shaft 21.

It is obvious that turning the shaft 20 through the swinging of the lever 25 will act, through the engagement of the inclined facets 23 and 23^a, to displace the valve 44 from its seat and admit air pressure to the pipe 43 and the cylinder 27 (see Figures 1 and 4). This is due to the fact that the shaft 21 is, at the time, held against turning by the sides of the link 34 embracing the flat section 22.

The action of the device is initiated through the swinging of the lever 25. The manner of doing this and the means employed, forming no part of my present invention, have not been illustrated and will not be described.

Normally the casing 14 is held in an upright position with the dash-pot 38 charged with a liquid, preferably of an oily substance, to a depth well above the plunger head 37. Referring now to Figure 1, it becomes obvious that the shaft member 20 may be subjected to a rotative movement in either direction by means of the lever 25, while its co-member 21 having its non-circular portion 22 between the guides 35 and 35^a, may not be thus rotated, but is subjected to a reciprocal movement when the relative positions of the inclined facet ends 23 and 23^a are moved out of alignment, thereby acting to displace the valve 44 from its seat, through the shaft member 21 pressing against the stem 48.

This admits air to the pipe 43, and also into the cylinder 27, pressing the piston 28 upward against the fulcrum lever 29, which in turn forces the plunger 37 downward into the dash-pot 38, against the resistance of the spring 32 and the liquid in the bottom of the dash-pot 38. The said liquid is for the purpose of producing a retarding action upon the plunger 37 and to that end, a small vent 40 is provided through which the liquid must pass, as the ball check valve 39 is closed during a downward movement of the same.

When the downward movement of the plunger 37 is completed, the circular enlargement 36 registers with the non-circular portion 22 of the shaft 21 (see Figure 2), thus permitting shaft 21 to turn, whereupon the pressure between inclined facet ends 23 and 23^a caused by spring 46, produces a turning effect upon shaft 21 which permits seating of the facet ends and of the valve 44, thereby cutting off fluid pressure from both cylinder 37 and pipe 43.

When atmospheric pressure is again attained below the piston 30 the fulcrum spring 32 immediately actuates a return movement of the plunger 37 and its component parts, but can not complete this

movement until the non-circular portion 22 is rotated, through the swinging of the lever 25, into position for passing the parallel guides 35 and 35^a over it, whereupon the movement is completed and the parts remain in their uppermost position preparatory to the next operation.

It should be understood that the shaft member 20 may be so adjusted by means of the adjustment screw 19 that the spring 46 will press the cam faces 23 and 23^a into alignment with each other and engage them sufficiently to cause the shaft 20 to rotate the shaft 21 when the latter has its non-circular portion 22 in register with the circular enlargement 36.

What I claim as my invention is:

1. In a pneumatically operated flange oiling device, the combination with means for applying the air, of means acting to cut off the air supply at the end of a fixed time period, said cut-off means acting independently of the means by which the air is applied.

2. In a pneumatically operated flange oiling device, an air applying mechanism, an air operated cut off means including a delaying mechanism and adapted to release the air applying mechanism at the end of a determined time period irrespective of the condition of the air applying mechanism.

3. In a pneumatically operated flange oiling device, in combination, a means for applying the operating air, a dash pot actuated by the operating air and means for cutting off the air controlled by the dash pot.

4. In a pneumatically operated device, means for applying the air, a dash pot, an actuating piston for the dash pot itself actuated by the air when applied, and an air cut off mechanism containing a member restrained by the dash pot until the latter reaches a definite point in its movement.

5. In a pneumatically operated flange oiling device, a means for automatically applying the air, and time controlled means for cutting off the air irrespective of the condition of the air applying mechanism.

6. In a pneumatically operated flange oiling device, a means for automatically applying air comprising an actuating couple consisting of two aligned rotative members having abutting cam faces, one of said members being reciprocative and having a flattened section, a dash pot device actuated by the air when applied and having a side bearing against the flattened section of the reciprocative member of the actuating couple, and adapted to clear said reciprocative member toward the end of the stroke of the dash pot.

7. In a pneumatically operated device, an axially movable valve controlling the air

- supply, rotative primary and secondary valve actuating members alined with the valve and having abutting cam faces, the secondary member being reciprocative to operate the valve, a dash pot device having engagement with the said secondary member to prevent turning thereof until the dash pot reaches a predetermined position.
- 10 8. In a pneumatically operated device, a valve controlling the air supply, valve operating means comprising primary and secondary rotative members having abutting cam surfaces, the secondary member being also reciprocative and having actuating connection with the valve, said secondary member having a flattened section, a dash pot piston actuated by the air supplied by the valve, a stem for said piston composed of two bars which span the flat section of the said secondary member and are bowed outwardly at a point to permit turning of said secondary member when the piston reaches the end of its stroke.
- 15 9. In a pneumatically operated device, a valve controlling the air supply, valve operating means comprising primary and secondary rotative members having abutting cam surfaces, the secondary member being also reciprocative and having actuating connection with the valve, said secondary member having a flattened section, a dash pot piston actuated by the air supplied by the valve, a stem for said piston composed of two bars which span the flat section of the said secondary member and are bowed outwardly at a point to permit turning of said secondary member when the piston reaches the end of its stroke.
- 20 10. In a pneumatically operated device, a valve controlling the air supply, valve operating means comprising primary and secondary rotative members having abutting cam surfaces, the secondary member being also reciprocative and having actuating connection with the valve, said secondary member having a flattened section, a dash pot piston actuated by the air supplied by the valve, a stem for said piston composed of two bars which span the flat section of the said secondary member and are bowed outwardly at a point to permit turning of said secondary member when the piston reaches the end of its stroke.

Signed at Chicago, Cook County, Illinois
this 29th day of March 1920.

CHARLES F. HOOFER.
